United States Patent

Des. 238,183
Patented Dec. 23, 1975

238,183

SPEAKER ENCLOSURE

Nils Lou, 1400 Englewood, St. Paul, Minn. 55104

Filed Mar. 22, 1974, Ser. No. 453,571

Term of patent 14 years

Int. Cl. D14—01

U.S. Cl. D26—14 G

FIG. 1

FIG. 2

FIG. 3

FIG. 4

FIG. 5FIG. 6FIG. 1 is a top plan view of a speaker enclosure showing my new design;

FIG. 2 is a bottom plan view of the speaker enclosure of FIG. 1;

FIG. 3 is an elevational view of the front and one side of the speaker enclosure design;

FIG. 4 is an elevational view of the other side of the speaker enclosure, the rear of the speaker being substantially similar to the side shown in FIG. 4 but reversed right to left.

FIG. 5 is a perspective view of the speaker enclosure as seen from the front and top of the speaker as shown in FIG. 1; and

FIG. 6 is a perspective view of the speaker enclosure as seen from the rear and bottom of the enclosure as shown in FIG. 1.

I claim:

An ornamental design for a speaker enclosure, as shown and described.
